COUNTING DEVICE

Beverly W. Taylor, Hermann, Mo. 65042

Filed Aug. 9, 1968, Ser. No. 13,075

Term of patent 14 years

Int. Cl. D9—04

U.S. Cl. D52—1

FIGURE 1 is a view in front elevation of my counting device;

FIGURE 2 is a view in rear elevation of the counting device shown in FIGURE 1;

FIGURE 3 is a view in right side elevation, as viewed in FIGURE 1, of the counting device shown in FIGURES 1-2;

FIGURE 4 is a view in left side elevation, as viewed in FIGURE 1, of the counting device shown in FIGURES 1-3;

FIGURE 5 is a top plan view of the counting device shown in FIGURES 1-4;

FIGURE 6 is a bottom plan view of the counting device shown in FIGURES 1-5; and

FIGURE 7 is a fragmentary sectional view, partially cut away, taken along the line 7—7 of FIGURE 1.

The essential features of the design reside in the full line portions thereof.

I claim:

The ornamental design for a counting device, as shown and described:
